UNITED STATES PATENT OFFICE.

VINCENT CHELENA, OF ATLANTA, GEORGIA.

CHECK GUARD.

1,406,611.

Specification of Letters Patent. Patented Feb. 14, 1922.

Application filed August 2, 1921. Serial No. 489,281.

To all whom it may concern:

Be it known that I, VINCENT CHELENA, a citizen of the United States, and resident of Atlanta, in the county of Fulton and 5 State of Georgia, have invented certain new and useful Improvements in Check Guards; and I do hereby declare that the following is a full, clear, and exact description such as will enable others skilled in the art to which 10 it appertains to make and use the same.

This invention has reference to improvements in check guards having for an object to provide a portable guard of the character mentioned which is of such construction as 15 will permit the same to be easily and quickly attached to a pen or pencil without alteration thereto and used for marking checks subsequent to their writing, in a manner to prevent fraudulent alteration or raising of 20 the same.

It is also an object of the invention to provide a check guard having a novel form of frame therefor, a portion of which is bent upon itself to provide a spring or yieldable 25 support for the check marking device.

Other objects will be in part obvious and in part pointed out hereinafter.

In order that the invention and its mode 30 of operation may be readily understood by persons skilled in the art, I have in the accompanying illustrative drawings and in the detailed following description based thereon, set out one embodiment of the same.

In these drawings:

Figure 1 is an elevation of a pen with the 35 check guard attached;

Figure 2 is a plan view of the guard frame blank;

Figure 3 is a front elevation of the guard;

Figure 4 is a side elevation of the same; 40 and,

Figure 5 is an end elevation thereof.

Having more particular reference to the drawings in connection with which like 45 characters of reference will designate corresponding parts throughout, my improved check guard or marking device comprises a frame or attaching clip indicated in its entirety by the numeral 1, this frame consisting 50 of a single piece of spring metal, one portion of which is looped upon itself as at 2, while the opposite portion is curved inwardly as at 3 whereby to provide means for effectually engaging the frame with a pen 55 4, or a pencil or other device to which it is desired to attach the guard. In this con-

nnection, it will be understood that due to the inherent resiliency of the frame 1, the curved portion 3 thereof will firmly and snugly engage the pen 4 and by consequence, 60 displacement of the same with relation thereto will be prevented. Engagement of the frame 1 with the pen 4 is rendered even more firm by reason of the inwardly disposed free portion of the looped part 2, which as will 65 be understood, will have bearing upon the adjacent peripheral surface of said pen 4.

The looped portion 2 of the frame 1 provides means for receiving the check marking device and in this connection, it is to be 70 noted that the outer side of said looped portion is cut away to provide a substantially rectangular opening 5, while apertured ears 6 are bent inwardly from the opposite ends of said looped portion and serve as effectual bearing means for a circular or barrel-like marking device 7. This device 7 is provided with a plurality of series of circumferentially disposed square pointed teeth 8 at intervals along its peripheral surface 80 whereby when the device 7 is rolled over a check or other piece of paper or material, it will form a plurality of parallel rows of square holes in the face of the same.

Particular attention is directed to the fact 85 that by the looped formation of the portion 2 of the frame 1, the inner side of said looped part by bearing upon the adjacent surface of the pen 4 will afford a resilient or spring support for the marking device 7 90 and by consequence, will cause the squared teeth 8 on said device to engage the paper or other material to be marked sufficiently to form the squared perforations therein.

In using my improved check guard, I 95 preferably roll the same over the reverse side of a check or other piece of material to be marked, thus forming a plurality of upstanding extensions on the face thereof, which, if attempts at altering or raising the 100 check are made, will be torn and by consequence will noticeably mutilate the check to such an extent as to prevent its fraudulent use. Furthermore, with tearing of the upstanding extensions formed on the face of 105 the check by the improved guard, it will be understood that the raising of a check subsequently to the making of an erasure will be prevented, since the ink used in the writing or raising operation will be permitted to 110 flow into the perforations formed by the torn upstanding extensions.

It is of course to be understood that my improved check guard may be formed of various sizes such as conditions or preference may dictate and furthermore, that the size of attaching device or frame therefor may be varied in size and shape to permit its engagement with either pens or pencils of different sizes, or various other articles, such as may be desired.

10 Manifestly, the construction shown is capable of considerable modification and such modification as is within the scope of my claims, I consider within the spirit of my invention.

15 I claim:

1. A check guard comprising an attaching frame formed of a single piece of spring metal having one portion thereof curved to permit of engagement with an article, and 20 a barrel-like marking device rotatably mounted on the opposite portion of said frame having a plurality of series of circumferentially disposed squared pointed teeth formed on its peripheral surface.

25 2. A check guard comprising an attaching frame formed of a single piece of spring metal having one portion thereof bent at substantially right angles and looped, the outer side of said looped portion being cut

away to form an opening, a barrel-like 30 marking device engaged in said opening and rotatably supported adjacent the outer side of said looped portion, having a portion thereof extended through said opening, and the remaining portion of said frame being 35 curved upon itself to permit the engagement with a supporting article.

3. A check guard comprising a frame formed of a single piece of spring metal, having one portion thereof bent at substantially right angles and looped, the outer side of said looped portion being cut away to provide a substantially rectangular opening, apertured ears on the opposite end of said outer side of the looped portion, a drum like 45 marking device rotatably mounted in said apertured bearings having a portion thereof extended outwardly through the rectangular opening, the opposite side of said attaching frame being curved inwardly to provide means for engaging the same with a supporting article, the inner side of said looped portion bearing against the supporting article whereby to provide a yieldable support for said drum-like marking device. 50 55

In witness whereof I have hereunto set my hand.

VINCENT CHELENA.
